RUBBER OVERSHOE

Justin Loewengart, New York, N. Y.

Application May 2, 1951, Serial No. 15,039

Term of patent 7 years

(Cl. D7—4)

To all whom it may concern:

Be it known that I, Justin Loewengart, a citizen of the United States, residing at the city of New York, Borough of Manhattan, county of New York, and State of New York, have invented a new, original, and ornamental Design for a Rubber Overshoe, of which the following is a specification, reference being had to the accompanying drawing, forming a part thereof.

In the drawing:

Fig. 1 is a side elevational view of a rubber overshoe, showing my new design, the opposite side presenting substantially the same appearance as the side shown;

Figure 2 is a top view.

I claim:

The ornamental design for a rubber overshoe, substantially as shown and described.

JUSTIN LOEWENGART.
